(57) **ABSTRACT**

Provided is a connector capable of smoothly performing floating while suppressing impedance mismatch. A receptacle unit of a connector includes: a fixed housing that is fixed to a substrate and has an opening portion penetrating through the fixed housing upward and downward; a floating housing accommodated in the opening portion of the fixed housing with a movable space and a movable space apart; and a plurality of contacts that are bridged between the fixed housing and the floating housing and have a support piece portion supported by the fixed housing, a support piece portion supported by the floating housing, and an elastically deformable elastic deformation portion interposed between these two support piece portions.

CROSS-REFERENCE TO RELATED APPLICATIONS AND PRIORITY

This patent application claims priority from PCT Patent Application No. PCT/JP2020/032908 filed Aug. 31, 2020. This patent application is herein incorporated by reference in its entirety.

TECHNICAL FIELD

The present disclosure relates to a connector with a floating mechanism.

BACKGROUND

Many connectors for high-speed transmission are formed by press-fitting a plurality of contacts side by side into an opening portion of a housing made of electrically insulating resin. In this type of connector, when the contact has a shape formed by bending a piece of metal into an L-shape or an arc-shape, an impedance mismatch occurs between the bent portion and the linear portion other than the bent portion. As a document disclosing a technique suppressing the impedance mismatch of this type of connector, Patent Document 1 can be taken up. A connector for substrate connection disclosed in Patent Document 1 is composed of a socket-type first connector and a plug-type second connector fitted into the first connector. The first connector of this Document 1 includes a fixed housing, a floating housing, and a plurality of contacts bridged between these housings. The contact of the first connector has a first spring portion and a second spring portion extending in an inverted V-shape, and an inverted curved portion interposed between their upper ends, and a partition member made of an electrically insulating synthetic resin material is arranged between the inverted curved portions of adjacent contacts. According to the technique of Patent Document 1, due to the action of the partition member arranged between the inverted curved portions, the difference in impedance between the inverted curved portion and the other portion extending linearly is narrowed, and the impedance mismatch is suppressed.

PRIOR ART REFERENCE

Patent Document

Patent Document 1: Japanese Patent Application Publication No. 2013-045739

SUMMARY

Problems to be Solved

However, in the case of the technique of Patent Document 1, there is a problem that although the impedance mismatch can be suppressed, due to the partition member between the inverted curved portions of the adjacent contacts, relative movement between the first connector and the second connector is regulated when fitting the second connector into the first connector, and it is difficult to smoothly perform floating, which is a movement absorbing errors in the attachment positions of the two connectors.

2

The present disclosure has been made in view of such a problem, and one of the objects is to provide a connector capable of smoothly performing floating while suppressing impedance mismatch.

5

Means for Solving the Problems

In order to solve the above problems, a preferred aspect of the present disclosure is a connector including a receptacle unit mounted on a first substrate and a plug unit mounted on a second substrate and connected to the receptacle unit, and electrically connecting the first substrate and the second substrate by connecting the receptacle unit and the plug unit, wherein the receptacle unit may include: a fixed housing that is fixed to the substrate and has an opening portion penetrating through the fixed housing upward and downward; a floating housing accommodated in the opening portion of the fixed housing with a movable space apart; and a plurality of contacts that are bridged between the fixed housing and the floating housing, and have a first support piece portion supported by the fixed housing, a second support piece portion supported by the floating housing, and an elastically deformable elastic deformation portion interposed between these two support piece portions, the elastically deformable elastic deformation portion may have two linear portions extending along wall portions of the fixed housing and the floating housing facing the movable space, and a flexible portion between upper ends of the two linear portions, and portions opposed to the flexible portion in the wall portions may be curved following a shape of the flexible portion.

In this aspect, the contact may have a terminal portion connected to the first support piece portion and a contact point portion connected to the second support piece portion, the fixed housing may have first wall portions opposed to each other so as to surround the opening portion, the floating housing may have a slot into which the plug unit is inserted, the floating housing may be provided with a through hole penetrating from a bottom surface toward the inside of the slot, and the contact may be press-fitted into the fixed housing and the floating housing such that the contact point portion is protruded into the slot via the through hole and the elastic deformation portion is accommodated in the movable space.

Further, the first wall portions may be provided with a plurality of first slits, and the first support piece portion of the contact may be accommodated and supported in the first slit.

Further, the floating housing may have second wall portions constituting an inner circumferential surface of the slot, the second wall portions may be provided with a plurality of second slits, and the second support piece portion of the contact may be accommodated and supported in the second slit.

Further, the contacts in each column may be arranged in such an arrangement order that two contacts for ground and two contacts for signal are taken as one group and the two contacts for signal are accommodated between the two contacts for ground, and a conductive resin member connecting the contacts for ground may be fixed to a bottom portion of the floating housing.

Further, a bottom surface of the floating housing may be provided with a conductive resin member.

Further, the conductive resin member may have a lower plate portion and a convex portion protruding upward from

a center of the lower plate portion, and the convex portion may be fitted in a groove provided on the bottom surface of the floating housing.

Further, the lower plate portion may have a shape in which four corners of a rectangular parallelepiped is protruded outward in a left-right direction, a pillar portion erecting upward may be provided at a tip end of the portion protruded outward, and the pillar portion may be in contact with two contacts for ground in a left side column and two contacts for ground in a right side column.

Further, holders may be provided at end portions on a front side and a rear side of an outer surface of the first wall portion, and an anchor plate may be mounted on the holder.

Effects

The present disclosure includes a receptacle unit mounted on a first substrate and a plug unit mounted on a second substrate and connected to the receptacle unit, and in a connector electrically connecting the first substrate and the second substrate by connecting the receptacle unit and the plug unit, the receptacle unit includes: a fixed housing fixed to the substrate and having an opening portion penetrating through the fixed housing upward and downward; a floating housing accommodated in the opening portion of the fixed housing with a movable space apart; and a plurality of contacts bridged between the fixed housing and the floating housing, and having a first support piece portion supported by the fixed housing, a second support piece portion supported by the floating housing, and an elastically deformable elastic deformation portion interposed between these two support piece portions, the elastically deformable elastic deformation portion has two linear portions extending along wall portions of the fixed housing and the floating housing facing the movable space, and a flexible portion between upper ends of the two linear portions, and portions opposed to the flexible portion in the wall portions are curved following a shape of the flexible portion. Thus, the wall portion of the fixed housing and the wall portion of the floating housing come to confront the flexible portion so as to cover the flexible portion, and variations in impedance between the flexible portion and other portions of the contact are reduced. Further, the movement of floating housing is not restricted by portions opposed to the flexible portion in the wall portion of the fixed housing and the wall portion of the floating housing. Therefore, it is possible to provide a connector capable of smoothly performing floating while suppressing impedance mismatch of the contact.

BRIEF DESCRIPTION OF DRAWINGS

FIG. 1A is a perspective view of a receptacle unit 93 of a connector 100 according to one embodiment of the present disclosure, and FIG. 1B is a perspective view of a plug unit 97 of the connector 100;

FIG. 2 is a perspective view of the receptacle unit 93 of FIG. 1A viewed from an opposite side;

FIG. 3 is a cross-sectional view of the receptacle unit 93 and the plug unit 97 fitted together;

FIGS. 4A and 4B are diagrams showing how the receptacle unit 93 floats in an X direction, and FIG. 4C is a diagram showing how the receptacle unit 93 floats in a Y direction;

FIG. 5A is a view of the receptacle unit 93 viewed from a +Z side, FIG. 5B is a view of the receptacle unit 93 viewed from a +Y side, FIG. 5C is a view of the receptacle unit 93

viewed from a -Z side and FIG. 5D is a view of the receptacle unit 93 viewed from an -X side;

FIG. 6 is a cross-sectional view taken along line A-A of FIG. 5B;

FIG. 7A is a perspective view of a fixed housing 1 of the receptacle unit 93, and FIG. 7B is a cross-sectional view taken along line A-A of FIG. 7A;

FIG. 8A is a perspective view of a floating housing 2 of the receptacle unit 93, and FIG. 8B is a cross-sectional view taken along line A-A of FIG. 8A;

FIG. 9 is a perspective view of a contact 3-j of the receptacle unit 93;

FIG. 10 is a perspective view of an anchor plate 4 of the receptacle unit 93;

FIG. 11 is a perspective view of a conductive resin member 5 of the receptacle unit 93;

FIG. 12A is a view of the plug unit 97 viewed from the +Z side, FIG. 12B is a view of the plug unit 97 viewed from the +Y side, FIG. 12C is a view of the plug unit 97 viewed from the -Z side, and FIG. 12D is a view of the plug unit 97 viewed from the -X side;

FIG. 13A is a cross-sectional view taken along line D-D of FIG. 12D, and FIG. 13B is an enlarged view within the frame G of FIG. 13A;

FIG. 14 is an enlarged view within the F frame of FIG. 12B;

FIG. 15A is a cross-sectional view taken along line H-H of FIG. 12A, and FIG. 15B is an enlarged view within the frame J of FIG. 15A;

FIG. 16 is an enlarged view within the frame K of FIG. 12C;

FIG. 17A is a perspective view of a housing 6 of the plug unit 97, and FIG. 17B is a cross-sectional view taken along line A-A of FIG. 17A;

FIG. 18 is a perspective view of a contact 7-j of the plug unit 97; and

FIG. 19 is a perspective view of an anchor plate 8 of the plug unit 97.

DETAILED DESCRIPTION

Hereinafter, a connector 100 according to one embodiment of the present disclosure is explained with reference to drawings. The connector 100 includes a receptacle unit 93 and a plug unit 97. The receptacle unit 93 is mounted on an electronic substrate, which is a first substrate. The plug unit 97 is mounted on an expansion board, which is a second substrate. By fitting a header 62 of the plug unit 97 into a slot 20 of the receptacle unit 93 and connecting the receptacle unit 93 and the plug unit 97, K (K is 144, for example) contacts 7-j (j=1 to K) of the plug unit 97 and K contacts 3-j (j=1 to K) of the receptacle unit 93 are electrically connected, respectively, and high-speed differential transmission of maximum number of Gbps due to PAM (Pulse Amplitude Modulation) is made possible.

In the following description, a fitting direction of the plug unit 97 with respect to the receptacle unit 93 is appropriately referred to as a Z direction, one direction orthogonal to the Z direction is appropriately referred to as an X direction, and a direction orthogonal to both the Z direction and the Y direction is appropriately referred to as a Y direction. In addition, the +Z side may be referred to as an upper side, the -Z side may be referred to as a lower side, the +X side may be referred to as a front side, the -X side may be referred to as a rear side, the +Y side may be referred to as a left side, and the -Y side may be referred to as a right side. Further, among the contacts 3-j (j=1 to K) of the receptacle unit 93

and the contacts 7-*j* (*j*=1 to K) of the plug unit 97, letter (G) is attached to the contacts 3-*j* and contacts 7-*j* for ground of differential transmission, and letter (S) is attached to the contacts 3-*j* and contacts 7-*j* for signal to distinguish between them.

As shown in FIG. 1A, FIG. 2, FIG. 5A, FIG. 5B, FIG. 5C, and FIG. 5D, the receptacle unit 93 has a fixed housing 1, a floating housing 2, contacts 3-*j* (*j*=1 to K), an anchor plate 4, and a conductive resin member 5.

As shown in FIG. 7, the fixed housing 1 has an opening portion 10 penetrating through the fixed housing 1 upward and downward, and wall portions 11 and 12, which are first wall portions surrounding the opening portion 10. The wall portions 11 are opposed to each other in the X direction with the opening portion 10 sandwiched therebetween, and the wall portions 12 are opposed to each other in the Y direction with the opening portion 10 sandwiched therebetween.

The upper and left and right edges of the outer surfaces of the front and rear wall portions 11 of the fixed housing 1 protrude outward as convex portions 111. In the middle of the outer surface of the wall portion 11, there is a middle plate 112 extending upward and downward. A positioning boss 113 is provided at the center of the lower surface of the wall portion 11. This positioning boss 113 is fitted into a positioning hole of an electronic substrate when fixing the receptacle unit 93 to the electronic substrate.

Holders 121 for mounting the anchor plate 4 are provided at end portions on the front side and rear side of the outer surface of the left and right wall portions 12 of the fixed housing 1. A lower end side between the two holders 121 on the outer surface of the wall portion 12 protrudes outward as a convex portion 122.

The lower sides of the inner surfaces of the left and right wall portions 12 of the fixed housing 1 are respectively provided with a column of K/2 slits 17-*j* arranged in the front and rear. On the upper sides of the inner surfaces of the wall portions 12 on the left and right, there are curved portions 14 curved inward in a quarter arc-shape, and there are inner edge portions 15 parallel to the inner surfaces on the curved portions 14.

As shown in FIG. 8A and FIG. 8B, the floating housing 2 has a slot 20 into which the header 62 of the floating housing 2 is inserted, and wall portions 21 and 22, which are the second wall portions constituting the inner circumferential surface of the slot 20. The wall portions 21 are opposed to each other in the X direction with the slot 20 sandwiched therebetween, and the wall portions 22 are opposed to each other in the Y direction with the slot 20 sandwiched therebetween. The floating housing 2 has dimensions to be accommodated in the opening portion 10 of the fixed housing 1.

The upper and left and right edges of the outer surfaces of the front and rear wall portions 21 of the floating housing 2 protrude outward as convex portions 211. The left and right lower ends of the convex portion 211 protrude outward.

The inner surfaces of the left and right wall portions 22 of the floating housing 2 are stepped surfaces in which the surface on the lower side protrudes with respect to the surface on the upper side. The lower sides of the inner surfaces of the left and right wall portions 22 of the floating housing 2 are respectively provided with a column of K/2 slits 26-*j* arranged in the front and rear. On the upper sides of the outer surfaces of the left and right wall portions 22, there are curved portions 24 curved outward in a quarter arc-shape, and there are outer edge portions 25 parallel to the outer surfaces on the curved portions 24.

As shown in FIG. 5A, FIG. 5C, and FIG. 8B, a bottom portion 23 forming the bottom of the slot 20 is bridged between the lower end portions of the front and rear wall portions 21 in the floating housing 2. The bottom portion 23 extends in a straight line in the front and rear. As shown in FIG. 8B, there are through holes 220 between the bottom portion 23 and the inner surfaces of the wall portions 22 on both left and right side thereof. The through holes 220 penetrate through from the bottom surface toward the inside 10 of the slot 20. The bottom surface of the floating housing 2 is provided with a conductive resin member 5. The bottom surface of the bottom portion 23 of the floating housing 2 is provided with a groove 230 for fixing the conductive resin member 5.

The contacts 3-*j* (*j*=1 to K) form a column of K/2 contacts 3-*j* on the left and a column of K/2 contacts 3-*j* on the right. As shown in FIG. 9, the contact 3-*j* has a terminal portion 31 extending in a left-right direction on one end side, a contact point portion 32 extending in an up-down direction on the other end side, a support piece portion 36 connected to the terminal portion 31, a support piece portion 37 connected to the contact point portion 32, and an elastic deformation portion 38 interposed between these two support piece portions 36 and 37.

The tip end of the contact point portion 32 is bent into a doglegged shape. There are claw portions 361 and 371 protruding outward on the side surfaces of the support piece portion 36 and the support piece portion 37.

The elastic deformation portion 38 has a flexible portion 380 rounded in a semicircular shape, two linear portion 381 and linear portion 382 extending downward from both ends of the flexible portion 380, a connecting portion 386 bent toward the support piece portion 36 side at the lower end of the linear portion 381 and connected to the upper end of the support piece portion 36, and a connecting portion 387 bent toward the support piece portion 37 side at the lower end of the linear portion 382 and connected to the lower edge of the support piece portion 37. The elastic deformation portion 38 can be elastically deformed frontward, rearward, leftward, and rightward.

As shown in FIG. 10, the anchor plate 4 has a main body portion 41, and a protruding portion 42 protruding downward from the lower edge of the main body portion 41. The upper edge of the side surface of main body portion 41 is provided with a convex portion 411 expanding laterally. There are claw portions 412 protruding outward below the convex portion 411 on the side surface of the main body portion 41. The protruding portion 42 is provided with a long hole 421.

As shown in FIG. 11, the conductive resin member 5 has a lower plate portion 51 in which four corners of a rectangular parallelepiped shape are protruded outward, a convex portion 53 protruding upward from the center of the upper surface of the lower plate portion 51, and pillar portions 59 erected upward from tip ends of the lower plate portion 51 that are protruded outward. The left and right width of the projection 53 is substantially the same as the left and right width of the groove 230 of the bottom portion 23 of the floating housing 2.

The fixed housing 1, the floating housing 2, the contacts 3-*j* (*j*=1 to K), the anchor plate 4, and the conductive resin member 5 are combined as follows.

As shown in FIG. 5A, FIG. 5C, and FIG. 6, the floating housing 2 is accommodated in the opening portion 10 of the fixed housing 1, two columns of contacts 3-*j* on the left and right are bridged between the floating housing 2 and the fixed housing 1, the conductive resin member 5 is mounted

in the groove 230 of the bottom portion 23 of the floating housing 2, and the anchor plate 4 is mounted on the holder 121 of the fixed housing 1.

Here, in FIG. 5C, in order to show the groove 230, the number of the conductive resin members 5 is six, but in reality, the conductive resin members 5 are mounted on the entire lower surface of the bottom portion 23.

As shown in FIG. 5A, between the wall portion 11 of the fixed housing 1 and the wall portion 21 of the floating housing 2 in the opening portion 10, there is a movable space 101 for making the floating housing 2 float forward and rearward, and between the wall portion 12 of the fixed housing 1 and the wall portion 22 of the floating housing 2, there is a movable space 102 for making the floating housing 2 float leftward and rightward. The contacts 3-j (j=1 to K) are arranged in such an arrangement order that two contacts 3-j (G) and two contacts 3-j (S) are taken as one group, and the two contacts for signal are accommodated between the two contacts for ground.

As shown in FIG. 6, the contact 3-j is press-fitted into the fixed housing 1 and the floating housing 2 from the lower side such that the contact point portion 32 is protruded into the slot 20 via the through hole 220, and the elastic deformation portion 38 is accommodated in the movable space 102. The support piece portion 36 of the contact 3-j is accommodated and supported in the slit 17-j. The support piece portion 37 of the contact 3-j is accommodated and supported in the slit 26-j.

The connecting portion 387 of the contact 3-j is in contact with the lower surface of the floating housing 2. The terminal portion 31 of the contact 3-j is exposed to the lower side of the lower surface of the fixed housing 1. The terminal portion 31 of the contact 3-j is soldered and fixed to the pad of the electronic substrate. Between the adjacent contacts 3-j, there is no partition of the electric insulating member, and only an air layer exists.

As shown in FIG. 6, a gap 120 is provided between the inner edge portion 15 of the fixed housing 1 and the outer edge portion 25 of the floating housing 2. On the lower side of the gap 120 in the movable space 102, the curved portion 14 of the wall portion 12 and the curved portion 24 of the wall portion 22 are curved along the shape of the flexible portion 380 of the elastic deformation portion 38.

The convex portion 53 of the conductive resin member 5 is fitted in the groove 230 of the bottom portion 23 of the floating housing 2. The two pillar portions 59 on the left side of the conductive resin member 5 are in contact with the two contacts 3-j (G) on the left side. The two pillar portions 59 on the right side of the conductive resin member 5 are in contact with the two contacts 3-j (G) on the right side. The four contacts 3-j (G) are electrically connected via the conductive resin member 5. The protruding portion 42 of the anchor plate 4 mounted on the holder 121 extends to the lower side of the lower surface of the fixed housing 1.

As shown in FIG. 1B, FIG. 12A, FIG. 12B, FIG. 12C, and FIG. 12D, the plug unit 97 has a housing 6, contacts 7-j (j=1 to K), and an anchor plate 8.

As shown in FIG. 17A and FIG. 17B, the housing 6 has a header 62 and a base portion 63.

The header 62 protrudes downward from the lower surface of the base portion 63. The left and right outer surfaces of the header 62 are each provided with a column of K/2 slits 66-j.

The slit 66-j on the left side has a U-shaped cross section surrounded by the right peripheral wall, the front peripheral wall, and the rear peripheral wall. The right side of the slit 66-j on the left side is open, and the front peripheral wall and

the rear peripheral wall are opposed to each other. The slit 66-j on the right side has a U-shaped cross section surrounded by the left peripheral wall, the front peripheral wall, and the rear peripheral wall. The left side of the slit 66-j on the right side is open, and the front peripheral wall and the rear peripheral wall are opposed to each other.

As shown in FIG. 17B, grooves 661 are provided in three peripheral walls of the slits 66-j on the left side and right side. The groove 661 of the front peripheral wall is recessed forward, the groove 661 of the rear peripheral wall is recessed rearward, the groove 661 of the left peripheral wall is recessed leftward, and the groove 661 of the right peripheral wall is recessed rightward.

A positioning boss 613 is provided at the center of the front and rear end portions of the upper surface of the base portion 63. The positioning boss 613 is fitted into the positioning hole of the expansion board when fixing the plug unit 97 to the expansion board. The upper edges of the front and rear side surfaces of the base portion 63 expand outward as outer edge portions 631. The outer edge portion 631 is provided with a holder 632 for mounting the anchor plate 8.

A column of K/2 through holes 67-j arranged in the front and rear is provided on each of the left side and right side of the center of the base portion 63 in the Y direction. The through hole 67-j penetrates through the base portion 63 upward and downward. The through hole 67-j on the left side is communicated with the slit 66-j on the left side, and the through hole 67-j on the right side is communicated with the slit 66-j on the right side.

The through holes 67-j on the left side and right side have a rectangular cross section surrounded by the left peripheral wall, the right peripheral wall, the front peripheral wall, and the rear peripheral wall. The left peripheral wall and the right peripheral wall are opposed to each other, and the front peripheral wall and the rear peripheral wall are opposed to each other in the through holes 67-j on the left side and right side. The peripheral wall of the through hole 67-j is connected to the peripheral wall of the slit 66-j.

As shown in FIG. 15A, two holding portions 679 and 678 constricted inward are provided at the upper end and lower end of the through holes 67-j on the left side and right side.

As shown in FIG. 17B, grooves 672 are provided in portions of the four peripheral walls of the left and right through holes 67-j excluding the two holding portions 679 and 678. The groove 672 of the front peripheral wall is recessed forward, the groove 672 of the rear peripheral wall is recessed rearward, the groove 672 of the left peripheral wall is recessed leftward, and the groove 672 of the right peripheral wall is recessed rightward. The orientation and depth of the groove 672 of the through hole 67-j are the same as the orientation and depth of the groove 661 of the slit 66-j.

The contacts 7-j (j=1 to K) form a column of K/2 contacts 7-j on the left and a column of K/2 contacts 7-j on the right. As shown in FIG. 18, the contact 7-j has a linear portion 72 extending in the up-down direction on one end side, a terminal portion 79 extending in the left-right direction on the other end side, and a connecting portion 80 interposed between the linear portion 72 and the terminal portion 79.

There is a claw portion 720 protruding outward at a position away from the lower end toward the upper side on the side surface of the linear portion 72. The upper end of the linear portion 72 is slightly wider than the portion below it. Further, this wider portion is provided with a long hole 721.

As shown in FIG. 19, the anchor plate 8 has two rectangular piece portions 81, a bridged portion 40 bridged between the lower ends of the two rectangular piece portions 81, and protruding portions 83 protruding upward from the

upper edges of the two rectangular piece portions **81**. There are claw portions **812** protruding outward on the side surfaces of the two rectangular piece portions **81**.

The housing **6**, the contacts **7-j** (j=1 to K), and the anchor plate **8** are combined as follows. The contacts **7-j** (j=1 to K) are press-fitted into the housing **6** from the upper side. The linear portion **72** of the contact **7-j** is inserted into the through hole **67-j**, and its tip end side passes through the through hole **67-j** and is held in the slit **66-j**. The terminal portion **79** of the contact **7-j** is exposed on the upper side of the upper surface of the housing **6**. The terminal portion **79** of the contact **7-j** is soldered and fixed to the pad of the expansion board.

The anchor plate **8** is mounted on the holder **632** of the housing **6**. The protruding portion **83** of the anchor plate **8** extends to the upper side of the upper end of the housing **6**. The linear portion **72** of the contact **7-j** extends in a straight line along the through hole **67-j** and the slit **66-j**. The portion of the linear portion **72** where the claw portion **720** is located is supported by the holding portion **678** of the lower side, and the thicker upper end portion of the linear portion **72** is supported by the holding portion **679** of the upper side.

As shown in FIG. 3, when the header **62** of the plug unit **97** and the slot **20** of the receptacle unit **93** are fitted together, the linear portion **72** of the contact **7-j** of the plug unit **97** and the contact point portion **32** of the contact **3-j** of the receptacle unit **93** come into contact with each other.

As shown in FIG. 4A and FIG. 4B, when the relative positions of the plug unit **97** and the receptacle unit **93** are displaced from each other in the front-rear direction, the contact **3-j** is twisted so that the linear portion **381** and the linear portion **382** are tilted to the opposite sides, and the receptacle unit **93** moves forward or backward in the opening portion **10**. Thereby, the positional displacement in the front-rear direction is eliminated.

Further, as shown in FIG. 4C, when the relative positions of the plug unit **97** and the receptacle unit **93** are displaced from each other in the left-right direction, the left and right contacts **3-j** are twisted so that one of the left and right linear portion **381** and linear portion **382** is widened and the other one of the linear portion **381** and linear portion **382** is narrowed, and the receptacle unit **93** moves leftward or rightward in the opening portion **10**.

The details of the configuration of the present embodiment are described above. The receptacle unit **93** of the connector **100** according to the present embodiment includes: a fixed housing **1** that is fixed to a substrate and has an opening portion **10** penetrating through the fixed housing **1** upward and downward; a floating housing **2** accommodated in the opening portion **10** of the fixed housing **1** with a movable space **101** and a movable space **102** apart; and a plurality of contacts **3-j** (j=1 to K) that are bridged between the fixed housing **1** and the floating housing **2** and have a support piece portion **36** supported by the fixed housing **1**, a support piece portion **37** supported by the floating housing **2**, and an elastically deformable elastic deformation portion **38** interposed between these two support piece portions **36** and **37**. The elastic deformation portion **38** has two linear portions **381** and **382** extending along a wall portion **12** and a wall portion **22** of the fixed housing **1** and floating housing **2** facing the movable space **102**, and a flexible portion **380** between upper ends of the two linear portions **381** and **382**, and portions opposed to the flexible portion **380** in the wall portion **12** and wall portion **22** are curved following the shape of the flexible portion **380**. Thus, the wall portion **12** and the wall portion **22** come to confront the flexible portion **380** so as to cover the flexible portion **380**, and variations in

impedance between the flexible portion **380** and other portions of the contact **3-j** are reduced. Further, the movement of the floating housing **2** is not restricted by portions opposed to the flexible portion **380** in the wall portions **12** and **22**. Therefore, it is possible to provide a connector **100** capable of smoothly performing floating while suppressing impedance mismatch of the contact **3-j**.

Although the embodiment of the present disclosure has been described above, the following modifications may be added to this embodiment.

(1) In the embodiment described above, the column of the contacts **3-j** (j=1 to K) of the receptacle unit **93** may be one column, or may be three columns or more.

(2) In the embodiment described above, separate conductive resin members **5** may be provided in the left side column and right side column of the contacts **3-j** (j=1 to K). In this case, one conductive resin member **5** is in contact with two contacts **3-j(G)** sandwiching the two contacts **3-j(S)**, and may electrically connect these two contacts for ground **3-j(G)**.

(3) In the embodiment described above, the number of the anchor plates **4** is not necessary to be four, and may be one to three, or may be five or more.

(4) In the embodiment described above, the number K of the contacts **3-j** may be 145 or more, or may be 143 or less.

What is claimed is:

1. A connector comprising a receptacle unit mounted on a first substrate and a plug unit mounted on a second substrate and connected to the receptacle unit, the connector electrically connecting the first substrate and the second substrate by connecting the receptacle unit and the plug unit, wherein, the receptacle unit comprises:

a fixed housing that is fixed to a substrate and comprise an opening portion penetrating through the fixed housing upward and downward;

a floating housing accommodated in the opening portion of the fixed housing with a movable space apart; and a plurality of contacts that are bridged between the fixed housing and the floating housing and comprise a first support piece portion supported by the fixed housing, a second support piece portion supported by the floating housing, and an elastically deformable elastic deformation portion interposed between these two support piece portions, the elastic deformation portion comprises:

two linear portions extending along wall portions of the fixed housing and the floating housing facing the movable space, and a flexible portion between upper ends of the two linear portions, the portions opposed to the flexible portion in the wall portions are curved following a shape of the flexible portion.

2. The connector according to claim 1, wherein a bottom surface of the floating housing is provided with a conductive resin member.

3. The connector according to claim 2, wherein the conductive resin member comprises a lower plate portion and a convex portion protruding upward from a center of the lower plate portion, and the convex portion is fitted in a groove provided on the bottom surface of the floating housing.

4. The connector according to claim 3, wherein the lower plate portion has a shape in which four corners of a rectangular parallelepiped is protruded outward in a left-right direction, a pillar portion erecting upward is provided at a tip end of the portion protruded outward, the pillar portion is in contact with two contacts for ground in a left side column and two contacts for ground in a right-side column.

11

5. The connector according to claim 1, wherein the contact comprises:

a terminal portion connected to the first support piece portion; and

a contact point portion connected to the second support piece portion,

the fixed housing comprises:

first wall portions opposed to each other so as to surround the opening portion,

the floating housing comprises:

a slot into which the plug unit is inserted, the floating housing is provided with a through hole penetrating from a bottom surface toward an inside of the slot, the contact is press-fitted into the fixed housing and the floating housing such that the contact point portion is protruded into the slot via the through hole and the elastic deformation portion is accommodated in the movable space.

6. The connector according to claim 5, wherein holders are provided at end portions on a front side and a rear side

12

of an outer surface of the first wall portion, and an anchor plate is mounted on the holder.

7. The connector according to claim 5, wherein a plurality of first slits are provided in the first wall portions, the first support piece portion of the contact is accommodated and supported in the first slit.

8. The connector according to claim 7, wherein the floating housing comprises second wall portions constituting an inner circumferential surface of the slot, and the second wall portions are provided with a plurality of second slits, the second support piece portion of the contact is accommodated and supported in the second slit.

9. The connector according to claim 8, wherein the contacts in each column are arranged in such an arrangement order that two contacts for ground and two contacts for signal are taken as one group, and the two contacts for signal are accommodated between the two contacts for ground, a conductive resin member connecting the contacts for ground is fixed to a bottom portion of the floating housing.
